(57) **CLAIM**

We claim the ornamental design for nut, as shown and described.

DESCRIPTION

FIG. 1 is a front, right-side, top perspective view of the first embodiment of a nut;

FIG. 2 is a front elevational view thereof, the rear elevational view is a mirror image thereof;

FIG. 3 is a right-side elevational view thereof, the left-side elevational view is a mirror image thereof;

FIG. 4 is a cross-section view thereof, the cross-section view is taken along the line 4-4 of FIG. 3; and

FIG. 5 is a cross-section view thereof, the cross-section view is taken along the line 5-5 of FIG. 3.

FIG. 6 is a front, right-side, top perspective view of the second embodiment of a nut;

FIG. 7 is a right-side elevational view thereof, the left-side elevational view is a mirror image thereof;

FIG. 8 is a right-side elevational view thereof, the left-side elevational view is a mirror image thereof;

FIG. 9 is a cross-section view thereof, the cross-section view is taken along the line 4-4 of FIG. 8; and,

FIG. 10 is a cross-section view thereof, the cross-section view is taken along the line 5-5 of FIG. 8.

The stippled shading represents a contrasting appearance of the threads as compared to the unstippled areas.

The broken lines in the drawings illustrate portions of the nut and form no part of the claimed design.
